UNITED STATES PATENT OFFICE

148,422

DESIGN FOR A COMBINED CONTAINER AND WRENCH SET UNIT

David Kane, Chicago, Ill.

Application July 17, 1946, Serial No. 131,664

Term of patent 14 years

(Cl. D80—5)

To all whom it may concern:

Be it known that I, David Kane, a citizen of the United States of America and residing at the city of Chicago, county of Cook, in the State of Illinois, have invented a new, original, and ornamental Design for a Combined Container and Wrench Set Unit, of which the following is a specification.

Reference is had to the drawing forming a part of the instant application in which

Fig. 1 is a plan view of the combined container and wrench set unit in closed position;

Fig. 2 is a front elevation of Fig. 1; and

Fig. 3 is a perspective view of the combined container and wrench set unit in open position.

I claim:

The ornamental design for a combined container and wrench set unit, as shown.

DAVID KANE.
